US0D1081977S

(12) **United States Design Patent** (10) **Patent No.:** **US D1,081,977 S**
(45) **Date of Patent:** **** Jul. 1, 2025**

(54) **NASAL ASPIRATOR**

(71) Applicant: **Qiang Zhang**, Guangdong (CN)

(72) Inventor: **Qiang Zhang**, Guangdong (CN)

(73) Assignee: **ZHONGSHAN XINGFU INDUSTRY AND TRADE CO., LTD.**, Guangdong (CN)

(**) Term: **15 Years**

(21) Appl. No.: **29/964,273**

(22) Filed: **Sep. 23, 2024**

(51) LOC (15) Cl. **24-02**

(52) U.S. Cl.

USPC **D24/115**

(58) **Field of Classification Search**

(57) **CLAIM**

The ornamental design for a nasal aspirator, as shown and described.

DESCRIPTION

FIG. 1 is a rear, right and top perspective view of a nasal aspirator, showing my new design;

FIG. 2 is a front, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures depict portions of the nasal aspirator that form no part of the claimed design. The nasal aspirator is shown with a symbolic break in its length and the appearance of any portion of the nasal aspirator between the break lines form no part of the claimed design.

1 Claim, 8 Drawing Sheets
